(57) **CLAIM**

The ornamental design for a core apparatus connectable to a variety of sensors, drug delivery devices, and other devices, as shown and described.

DESCRIPTION

FIG. 1 is a top plan view of a core apparatus connectable to a variety of sensors, drug delivery devices, and other devices illustrating my new design;

FIG. 2 is a front view thereof;

FIG. 3 is a bottom plan view thereof; and,

FIG. 4 is a front perspective view thereof.

The broken lines shown in FIG. 3 represent portions of the core apparatus connectable to a variety of sensors, drug delivery devices and other devices that form no part of the claimed design.

1 Claim, 4 Drawing Sheets
